(74) Attorney, Agent, or Firm—Jerome L. Jeffers

(**) Term: **14 Years**

(57) **CLAIM**

(21) Appl. No.: **29/161,225**

The ornamental design for a set of icons for display on a glucose meter, as shown and described.

(22) Filed: **May 28, 2002**

DESCRIPTION

(51) LOC (7) Cl. **14-02**
(52) U.S. Cl. **D14/488**
(58) Field of Search D14/485-95; D18/24-33;
D19/6; D20/11; D21/324-33; 345/700-26,
764-862; D24/169; 422/82.05; 250/339.12

The single FIGURE is a front view of a set of icons for display on a glucose meter showing our new design.
The broken line shown of the glucose meter is for illustrative purposes only and forms no part of the claimed design.
